George Graff, Toledo, Ohio, assignor, by mesne assignments, to National Laboratories, Inc., Toledo, Ohio, a corporation of Ohio

Application February 28, 1951, Serial No. 14,332

Term of patent 14 years

(Cl. D91—3)

To all whom it may concern:

Be it known that I, George Graff, a citizen of the United States, and resident of Toledo, in the county of Lucas and State of Ohio, have invented a new, original, and ornamental Design for a Detergent Mixing Device, of which the following is a specification, reference being had to the accompanying drawing, forming a part thereof.

In the drawings, Fig. 1 is a perspective view of a detergent mixing device embodying my new design; Fig. 2 is a side view thereof; Fig. 3 is a front view; Fig. 4 is a bottom view; and Fig. 5 is a rear view.

I claim:

The ornamental design for a detergent mixing device, substantially as shown.

GEORGE GRAFF.
